UNITED STATES PATENT OFFICE.

CHARLES L. WAGANDT, OF BALTIMORE, MARYLAND, ASSIGNOR TO THE NATIONAL ENAMELING & STAMPING COMPANY, OF NEW YORK, N. Y., A CORPORATION OF NEW JERSEY.

LAMP-BURNER.

1,162,714.

Specification of Letters Patent. Patented Nov. 30, 1915.

Application filed July 2, 1915. Serial No. 37,635.

To all whom it may concern:

Be it known that I, CHARLES L. WAGANDT, a citizen of the United States, residing at Baltimore, in the State of Maryland, have 5 invented certain new and useful Improvements in Lamp-Burners, of which the following is a specification.

This invention relates to improvements in lamp burners and has particular reference 10 to that form of burner wherein wicks are employed to feed the oil to the point of ignition which burners are provided with flame spreaders.

In the class of devices to which the invention is particularly adapted, the wick is confined between concentric wick tubes and the flame spreader is provided with a flange that seats on the outer end of the wick. Also in said class of devices it has been 20 common to provide a stationary central rod extending vertically from a rigidly-secured point in the inner wick tube and projecting up through the flame spreader to serve as a guide on which the spreader may move vertically as the wick is either raised or lowered. As heretofore constructed these permanently rigid guide rods have been found objectionable for various reasons, some of which are, that their outer or upper ends are 25 provided with a stop that screws onto said end and which must be removed before the spreader can be detached and is therefore liable to be mislaid or lost when removed. Another objection is that the position or location of this detachable stop is such as to 30 subject it to the action of extreme heat because it is directly over the top of the spreader, and difficulty is therefore often experienced on removing the stop as the result of the action of the heat thereon. A further objection to those permanently rigid guide rods is, that when the spreader is detached for 35 cleaning purposes, the rod remains in the center of and projects above the wick tubes where it materially interferes with and prevents access to the wick tubes and sometimes becomes bent because of such projection, and when bent interferes with the ready replacement of the spreader.

50 My invention therefore has for its object to provide an improved flame spreader guide and attaching device, that will be entirely free of all of the objections above-mentioned and which may be permanently connected to

the flame spreader so as to form a part thereof; will be removed with the spreader and will be connected with the wick-tubes at a point entirely removed from the flame or the extreme heat of the latter and therefore readily removable. Incidentally the construction will also serve the usual function as an extinguisher. 55

With these, and other objects in view, the inventive idea is illustrated in the accompanying drawings wherein,— 65

Figure 1, shows a central vertical section through the upper portion of the wick-tubes and the flame spreader to which my invention is applied. Fig. 2, is a sectional plan of the wick-tubes,—the section being 70 taken on the line 2—2 of Fig. 1. Fig. 3, shows the detached spreader and the guide rod permanently connected therewith. Fig. 4, illustrates the same in inverted or bottom plan. Fig. 5, shows the guide rod in 75 side elevation, the spreader being omitted. Fig. 6, is a view similar to that in Fig. 1, but showing a modified form of guide rod and connection with the wick tubes. Fig. 7, shows the spreader and guide rod of the 80 modified form detached and in side elevation. Fig. 8, illustrates the latter in bottom plan, and Fig. 9, shows a sectional elevation of the modified form of guide rod.

Referring to the drawings by numerals, 85 10, designates an outer wick tube, 11, the inner wick tube and 12, the wick between said tubes. In practice suitable means is employed to raise and lower the wick with respect to said tubes but this feature is 90 deemed unimportant to the present invention, and therefore is not illustrated.

The flame spreader may differ materially in construction from that shown in the accompanying drawing, and the invention is 95 therefore not to be restricted in this respect. In the present instance however the spreader is shown as having a cylindrical portion 13; a cap 14, at the upper end thereof and a wick ring 15, with an annular lateral flange 100 16, that projects over the top of the wick. The wick ring is rigidly secured to the lower part of the cylindrical portion and is provided with a central bottom plate 17, which is sustained from the ring by means 105 of radial arms 18,—the whole forming a spider-like structure that is rigid with the spreader. The plate 17, is provided with a

central perforation 19, and the cap 14, also has a central perforation 20, in vertical alinement with the perforation 19.

A guide stem 21, extends vertically through the spreader, passing loosely through the perforations 19 and 20, and said stem is provided at its upper projecting end with a permanently-attached head 22, and below the plate 17, is further provided with a stop projection 23. It will thus be understood that while the guide stem is loose with respect to the spreader and allows the latter to move longitudinally thereon, such movement is restricted in one direction by the permanently-attached head 22, on the stem and is restricted in its movement in a reverse direction by means of the rigid stop projection 23, on the stem. This latter stop 23, may have a variety of forms and shapes, but in the present instance its form is that of a washer that rigidly embraces the stem. It will also be understood that the stem 21, is permanently connected to the spreader and neither can be removed from the other. It is also to be particularly noted that the stem has no detachable head, nut or other device at its outer end over the top of the spreader cap where the heat is obviously intense.

30 Down inside of the inner wick tube 12, I provide a crosswise spider or plate 24, that is rigid with respect to said tube and therefore has no vertical movement therein, the object of which is to provide a connection 35 below the intense heat of the burner at which the lower end of the guide stem may be detachably secured and thereby avoid the action of such heat on the detachable connection. The means employed to effect this detachable connection of the guide stem below 40 the spreader may also vary in construction, but in the form of device shown in Figs. 1 to 5, inclusive, the lower end 25, of the stem is provided with exterior screw-threads 26, 45 which latter screw into a threaded perforation that is provided in the rigid plate 24, as shown in Fig. 1. By this means the lower end of the guide stem 21, is detachably connected down in the inner wick tube at a 50 point removed from the upper edge of the wick-tubes and much below the flame spreader, consequently the intense heat at and around the spreader cannot affect the threaded connection of the stem.

55 The permanently-attached head 22, at the outer end of the stem is of ample size to afford a broad stop for the flame spreader when the latter is raised by the wick and to also enable the stem to be rotated independently of the spreader in engaging or disengaging it with the rigid plate in the wick tube.

The plate 24, down in the inner wick tube is preferably provided with a concave central portion 27, at the center of which is

the threaded perforation, and by means of this formation the threaded end of the stem is readily brought into register with the threaded perforation for connection therewith.

In the modified structure shown in Figs. 6 to 8, inclusive, the wick-tubes, wick and spreader are of the same construction as illustrated in Figs. 1, 3 and 4,—the difference being in the form of connection between the lower end of the guide stem and a stationary device in the inner wick tube. In this modified form I provide a spider or plate 28, that is rigid with the inner wick-tube but which has a comparatively short vertical post 29, which latter has its upper end screw threaded and terminating below the upper ends of the wick-tubes and also below the plate 17, at the bottom of the flame spreader. In this modified form the guide stem 30, also passes freely through the cap 14 and plate 17, of the spreader and has the stop head 31, at the upper and outer end and a stop flange 32, at its lower inner end. A threaded socket 33, is provided in the lower end of this stem and the bottom face 34, of the stop flange is concaved around the socket entrance. By means of this construction the lower socket end of the guide stem will be brought into ready registration or alinement 95 with the upper threaded end of the post 29, when the lower end of the flame spreader is lowered into the inner wick-tube and a few revolutions of the permanently-attached head 31, at the outer end of the stem will 100 effect a rigid connection between the lower end of the stem and the post.

It will thus be seen that in both forms of devices the guide stem is a permanent part of the spreader and cannot be detached because of the head at the outer side and the stop at the inner side of the spreader; that the connection is made at a point much below that where the intense heat is located; that the spreader is free to move on the stem 110 as the wick is raised or lowered and therefore free rotation of the spreader on the stem is permitted; that no central rod projects from the wick tube when the spreader is detached and that wobbling of the spreader 115 on the guide stem is prevented because of the two bearing perforations 19 and 20, at the upper and lower portions of the spreader.

Having described my invention I claim,—

1. A flame spreader for oil burners having an annular shell, and a guide stem carried by the spreader and permanently attached thereto said stem having a head at its outer end and at its inner end provided with screw threads and the spreader having 125 a restricted movement longitudinally on the stem.

2. A flame spreader for oil burners having an annular shell with a cap plate at the outer side and a guide stem carried by and 130

permanently attached to the spreader said stem having a restricted longitudinal movement through the cap plate and shell and provided with means at its inner end to detachably connect it with an oil burner.

3. A flame spreader for oil burners having an annular shell with a cap at its upper side and a plate with openings therein at its lower side, of a guide stem carried by and extending through the shell and having its ends projecting through the cap and plate respectively and means for preventing detachment of the shell from the stem.

4. A flame spreader for oil burners having an annular shell with a cap at its upper side and a plate with openings therein at its lower side, of a guide stem carried by and extending through the shell and having its ends projecting through the cap and plate respectively; a head at the outer end of the stem and a stop on the stem beyond the plate at the lower side of the spreader.

5. In an oil burner the combination with the wick-tubes, of a flame spreader having an annular shell; a guide stem carried by and permanently attached to the spreader, and means for detachably engaging the stem below the upper end of the wick tubes.

6. In an oil burner the combination with the wick tubes, of a flame spreader; a guide stem permanently attached to the spreader but loosely engaging the latter said stem projecting below the inner end of the spreader and into the inner wick tube and

means in the wick tube for detachably connecting the spreader stem.

7. In an oil burner the combination with the wick tubes, of a flame spreader; a guide stem passing freely through the spreader and provided with means at opposite sides of the spreader to permit restricted movement of the latter thereon and means in the inner wick tube for detachably engaging the inner end of the spreader stem.

8. In an oil burner the combination with the wick tubes, of a flame spreader having a cap at one side and a plate at the other side,—said cap and plate having aligned perforations; a guide stem extending freely through said perforations; means on the stem to limit the movement of the spreader thereon in both directions and means for detachably securing the inner end of the spreader stem in the inner wick tube.

9. In an oil burner the combination with the wick tubes, of a flame spreader having an annular shell; a guide stem carried by the spreader; a head permanently carried on the outer end of the stem and means for detachably connecting the inner end of the guide stem in the inner wick tube.

In testimony whereof I affix my signature in presence of two witnesses.

CHARLES L. WAGANDT.
